MATTRESS TICKING

Sidney E. Blumenthal, New Orleans, La.

Application October 13, 1939, Serial No. 299,392

1 Claim. (Cl. 139—416)

This invention relates to mattress ticking and more particularly to a mattress ticking having a raised or embossed pattern on the display surface thereof.

5 Heretofore in the manufacture of woven ticking for mattresses, the pattern-forming yarn or filler consisted of flat threads or strands woven into the fabric during the manufacture thereof to produce a selected surface pattern or design in simulation 5
10 of damask. The pattern or design thus produced, however, presented a flat smooth appearance instead of a raised or embossed effect which was a deterrent factor from a sales standpoint in that the finished mattress had the appearance of 10
15 being covered with ordinary printed ticking instead of having the desired damask effect.

The object of the present invention is to provide a mattress ticking, the pattern-forming filler of which consists of a core of natural yarn having 20
25 a binder spirally wound around the same to provide a filler of appreciable thickness so that, when said filler is woven into the fabric to form a selected pattern or design, said pattern or design will have a raised or embossed effect in simulation 20
25 of high grade damask.

A further object of the invention is to provide an embossed mattress ticking which can be manufactured at very little cost and sold in competition with cheaper grades of mattress ticking.

30 Further objects and advantages will appear in the course of the following description.

In the drawing:

Figure 1 is a plan view of a portion of a strip or bolt of ticking fabricated in accordance with 35 the present invention.

Figure 2 is an edge view.

Figure 3 is a side elevation of a portion of one of the natural yarn fillers.

Figure 4 is a similar view of the cord or binder;

40 Figure 5 is a front elevation showing the manner in which the binder is wound in spiral form around the natural yarn to prevent disintegration of the yarn fibers, and

Figure 6 is a detail sectional view.

45 In carrying the invention into effect, I provide a plurality of pattern-forming filler strands 5 preferably formed of natural yarn and of greater thickness than the individual strands constituting the fabric body of the ticking, as shown. I then take a relatively thin binder 6 also preferably

formed of yarn and wind said binder spirally around the exterior of the filler 5 so as to prevent disintegration of the yarn filaments and produce a continuous cylindrical filler of the desired length and thickness which filler is woven into the ticking 7 by means of a Jacquard loom during the manufacture of the ticking so as to produce the desired surface design or pattern. As the fillers 5 are substantially cylindrical and of greater thickness than the weft and warp strands 5
10 of the ticking, said fillers will give a raised or embossed effect to the surface design or pattern on the ticking in simulation of high grade damask. As far as I am aware, mattress ticking has never been constructed in this manner. The ordinary 15 imitation damask ticking does not have a raised or embossed design effect owing to the fact that the fillers are flat and smooth and when woven into the ticking present a correspondingly flat surface pattern effect instead of the desired embossed effect produced by my novel form of 20 natural yarn fillers.

While I prefer to use my fillers in the manufacture of mattress ticking, it will, of course, be understood that said fillers may, if desired, be 25 woven into other kinds of material, such as upholstered cloth and the like.

A mattress ticking constructed in accordance with the present invention costs no more to weave than other mattress tickings, and owing to the 30 construction of my improved natural yarn fillers, the design or pattern on the display surface of the finished ticking will present a raised or embossed effect so as to give the ticking the appearance of high grade damask.

Having thus described the invention, what is 35 claimed as new is:

A mattress ticking comprising interwoven fabric strands, and pattern-forming filler strands of greater thickness than the fabric strands interwoven therewith and each consisting of relatively long individual natural yarn fibers loosely bunched together in substantially cylindrical form and provided with an exterior relatively thin natural yarn binder spirally encircling the 40 same without appreciably compressing the yarn of the filler strands, said filler strands projecting above the display surface of the ticking to produce 45 an embossed pattern effect.

SIDNEY E. BLUMENTHAL.
